CLAIM

The ornamental design for a utility light with a pair of adjustable supporting attachments, as shown and described.

DESCRIPTION

FIG. 1 is a right side rear perspective view of a utility light with a pair of adjustable supporting attachments showing my new design with the broken line showing for illustrative purposes only and forming no part of the claimed design; FIG. 2 is a front elevational view thereof; FIG. 3 is a top plan view thereof; FIG. 4 is a right side view thereof; FIG. 5 is a left side view thereof; FIG. 6 is a rear elevational view thereof; FIG. 7 is a bottom plan view thereof; FIG. 8 is similar to FIG. 1 but showing one of the attachments, which incorporates a magnet, in an alternate position; and, FIG. 9 is similar to FIG. 1, but showing one of the attachments, in the form of a hook, in an alternate position.
